ABSTRACT

A collapsible load-supporting pallet having a pair of elongated members with an upright arm on each end. A raised central portion in each of the elongated members has a vertically disposed pintle therethrough pivotally connecting the two elongated members. A flat member is removably supported by the upright arms and the raised central portions on the elongated members. A laterally disposed clip pivotally attached to each of the upright arms, releasably holds the flat member in its assigned position on the elongated members. A resilient member on the pintle yieldably urges the two elongated members apart so that they may be pivoted together to facilitate storage when the flat member is removed.

COLLAPSIBLE PALLET FOR FREIGHT AND CARGO

BACKGROUND OF THE INVENTION

This invention relates to load-supporting pallets generally, and more particularly to a collapsible pallet of the type commonly used by the shipping industry in handling freight, and moving it to and from warehouses and loading docks. Pallets presently in use are extremely bulky, and consequently create a storage problem for the shipper. They are also relatively expensive to produce, so the shipper is understandably reluctant to abandon them at their destination.

In the instance of wooden pallets, which are extremely heavy as well as expensive, the shippers incur considerable cost in moving them with the freight to the consignee, and having them returned for re-use. Fully cognizant of this situation, the applicant has invented a sturdy, fully collapsible, light weight pallet, which can be readily disassembled and compacted to facilitate storage and greatly reduce shipping charges.

SUMMARY OF THE INVENTION

This invention comprises a pair of elongated members 10 and 12 having on each end thereof an upright arm 14. A pair of inverted 'U' shaped sections 16 and 18 are provided in the central portions of the elongated members 10 and 12 respectively. A vertically disposed pindle 20, through the inverted 'U' shaped sections 16 and 18, pivotally connects the two elongated members 10 and 12. A flat member 21 is supported laterally by the upright arms 14 and the inverted 'U' shaped sections 16 and 18 in the elongated members 10 and 12 respectively. A laterally disposed clip 22, pivotally attached to each of the upright arms 14, holdably engages the periphery of the flat member 21. A resilient member 30 on the pindle 20 yieldably urges the two elongated members 10 and 12 apart.

DESCRIPTION OF THE DRAWING

FIG. 1 is an elevation view of the pallet comprising the applicant's invention, showing a carton 28 thereto attached by the adjustable holding straps 26.

FIG. 2 is a top plan view, taken substantially on plane 2-2 in FIG. 1, showing the laterally disposed 'U' shaped clips 22 on the upright arms 14.

FIG. 3 is a bottom plan view, taken substantially on plane 3-3 in FIG. 1, showing the elongated members 10 and 12 in a fully extended position.

FIG. 4 is an enlarged section view, taken substantially on plane 4-4 in FIG. 2, showing structural details of the laterally disposed 'U' shaped clips 22 on the upright arms 14.

FIG. 5 is an enlarged section view, taken substantially on plane 5-5 in FIG. 3, showing the smaller inverted 'U' shaped section 16 in the elongated member 10, and the resilient bushing 30 fully compressed.

FIG. 6 is an enlarged section view, taken substantially on plane 6-6 in FIG. 3, showing the larger inverted 'U' shaped section 18 in the other elongated member 12.

FIG. 7 is an enlarged section view, similar to FIG. 6, showing the resilient bushing 30 in its fully expanded position, holding the elongated members 10 and 12 apart.

FIG. 8 is a top plan view, showing the elongated members 10 and 12 detached from the flat member 21, and pivoted to a fully compacted position.

CONSTRUCTION

For a more detailed description of the invention, reference is made to the drawing in which numerals 10 and 12 designate a pair of elongated members having on each end thereof an upright arm 14. A pair of inverted 'U' shaped sections 16 and 18 of different widths are provided in the elongated members 10 and 12 respectively. A vertically disposed pindle 20 through each of the inverted 'U' shaped sections 16 and 18, pivotally connects together the elongated members 10 and 12 for limited relative movement.

A flat member 21 is laterally supported on the upright arms 14, and the inverted 'U' shaped sections 16 and 18 on the elongated members 10 and 12 respectively. A laterally disposed 'U' shaped clip 22, pivotally attached to each of the upright arms 14, holdably engages the periphery of the flat member 20. A screw 23, through an opening 24 in the upper side of each 'U' shaped clip 22, retains the flat member 21 in its assigned position.

A loop 25 on each of the 'U' shaped clips 22, slidably retain therethrough a pair of adjustable holding straps 26. A load, such as the carton 28 shown in FIG. 1, is releasably held on the flat member 21 of the pallet by the adjustable holding straps 26. A resilient bushing 30, on the vertically disposed pindle 20, yieldably urges the two elongated members 10 and 12 apart, to the relative positions shown in FIG. 7 of the drawings.

The preceding discussion completes a description of the structural details of the applicant's invention herein disclosed; however, to facilitate a more thorough comprehension and appreciation of the subject matter, a brief discussion of the manner in which the pallet is used so as to fulfill its intended function is immediately hereinafter set forth.

USE AND OPERATION

When the applicant's pallet is not in use, it may be readily disassembled and collapsed. This is done by pivoting the 'U' shaped clips 22 on the upright arms 14 so as to release the flat member 21, which is then removed from the elongated members 10 and 12. The resilient bushing 30 thereupon immediately expands, and moves the two elongated members 10 and 12 apart to the relative positions shown in FIG. 7.

The elongated 10 and 12 can then be pivoted together to the compacted positions shown in FIG. 8. In this collapsed condition the pallet occupies only a fraction of the space required by the assembled unit, thereby facilitating storage, and reducing considerably the freight and transportation costs involved in returning such pallet to the shipper.

Based upon the foregoing discussion, the applicant is of the opinion that his invention has fulfilled a long-felt need in the field of pallets, and that he has accordingly made a valuable contribution to the related art. However, while the invention was described with reference to the structural details of a single embodiment, it will be appreciated by those familiar with the art that the principles involved are susceptible of numerous other practical adaptations.

I therefore claim as new, and desire to secure by Letters Patent:

1. A collapsible pallet comprising two elongated members, an upright arm on each end of the elongated members, a raised central portion in each of the elongated members, a vertically disposed pintle through the raised central portions pivotally connecting together the two elongated members, a flat member removably supported by the upright arms and the raised central portions on the two elongated members, means on the upright arms for holdably engaging the flat member, and a resilient member on the vertically disposed pintle yieldably urging the two elongated members apart, such resilient member moving the two elongated members apart when they are detached from the flat mem-

ber so that they can be pivoted together and brought into a relatively compacted relationship.

2. The collapsible pallet of claim 1 in which the raised central portion in each of the elongated members comprises an inverted 'U' shaped section.

3. The collapsible pallet of claim 2 in which the means on the upright arms for holdably engaging the flat member comprises a laterally disposed clip pivotally attached to each of the upright arms.

4. The collapsible pallet of claim 3 in which the laterally disposed clip comprises a 'U' shaped member.
